UNITED STATES PATENT OFFICE

LIONEL STRASSBURGER, CHARLES NELSON, AND WALTER G. BARKER, OF NEW YORK,
N. Y., ASSIGNEES TO S. STERNAU & COMPANY, OF BROOKLYN, NEW YORK, A COPARTNERSHIP.

DESIGN FOR A TOWEL-RACK.

41,567.

Specification for Design.

Patented July 11, 1911.

Application filed February 11, 1911. Serial No. 608,138. Term of patent 7 years.

To all whom it may concern:

Be it known that we, LIONEL STRASSBURGER, a citizen of the United States, and a resident of the borough of Manhattan, city, county, and State of New York, and CHARLES NELSON and WALTER G. BARKER, citizens of the United States, and residents of the borough of Brooklyn, county of Kings, city and State of New York, have invented a new, original, and ornamental Design for a Towel-Rack, of which the following is a specification, reference being had to the accompanying drawings, forming a part hereof, in which—

We claim:

The ornamental design for towel rack, as shown.

LIONEL STRASSBURGER.
CHARLES NELSON.
WALTER G. BARKER.
